[57] CLAIM

The ornamental design for a table for artists or the like, substantially as shown and described.

DESCRIPTION

FIG. 1 is a front perspective view of a table for artists or the like, showing my new design;

FIG. 2 is a rear elevational view thereof;

FIG. 3 is a side elevational view thereof;

FIG. 4 is a view with the same aspect as FIG. 3, showing the table top in an open position;

FIG. 5 is a rear elevational view thereof, showing the table top in an open position; and

FIG. 6 is a front perspective view of another species thereof.

FIG. 1

FIG. 2

FIG. 3

FIG. 4

FIG. 5

FIG. 6
